UNITED STATES PATENT OFFICE.

JULES J. BRELL, OF NEW YORK, N. Y.

SCOURING DEVICE.

Application filed January 15, 1927. Serial No. 161,277.

This invention relates to a device used for scouring pots, pans, dishes, bottles or other household utensils and has for its object to provide an abrasive material and improved holder for the same, permitting such abrasive material to be both economically held and used.

A further object of this invention is to provide an improved holder for an abrasive polishing material, whereby such material can be maintained in a convenient and uniform shape despite hard use and will be so held that it cannot cut or mar the fingers while being used for polishing or other purposes.

With these objects and such other objects as may hereinafter appear in view, I have devised the particular arrangement of parts hereinafter set forth and more particularly pointed out in the claims appended hereto.

Reference is to be had to the accompanying drawing, forming a part hereof in which

Figure 1 is a side elevation of my improved scouring or polishing device, with parts being broken away to disclose construction;

Figure 2 is a vertical sectional view of a part of the same;

Figure 3 is a side elevation, partly in section of a modified form of device;

Figure 4 is a sectional view on the line 4—4 of Figure 3, looking in the direction of the arrows;

Figure 5 is a side elevation partly in section of a further modification; and

Figure 6 is a side elevation of a still further modification.

Throughout the various views of the drawings, similar reference characters designate similar parts.

In the embodiment of my invention disclosed in Figure 1, 1 indicates the outer covering or casing of the device. This casing or covering is made of any suitable resilient material and is preferably waterproof or water-repellent, so that it will maintain its shape while being used in water. The covering 1 may thus be made of rubber, waterproof fabric, very thin metal or the like. It is, as was heretofore stated, preferably made resilient, although it should possess sufficient rigidity or stiffness to maintain its shape during use and prevent its contents, consisting of an abrasive 2 from becoming misshapen or distorted. The abrasive substance 2 may be of any suitable material and preferably consists of steel wool which is tightly compacted into the casing or cover 1 so that the inherent

resiliency of this wool 2 combined with the resiliency of the covering 1 causes the material 2 to be maintained in position within the covering. It is also desirable to secure such material further in place by the use of a water-proof adhesive indicated at 3, with which the inner face of the covering 1 may be coated.

At 4 is shown a stiffening member or block which is inserted into one of the ends of the casing or cover 1, this block tending to maintain the casing in a substantially cylindrical form and also to add a desirable stiffness to the construction. The casing or cover 1 is provided with a plurality of circumferential grooves 5, which are spaced apart at desired distances and which naturally provide weakened parts on the casing or lines upon which parts of the casing may be torn away to expose parts of the abrasive material 2.

Located between the grooves 5 are thickened areas 6 and these areas 6 are provided with cut away portions 7 at which are located triangular shaped apertures 8.

It will be seen from Figures 1 and 2 that on one side of the covering, these apertures 8 are located in alternating ribs 6 and on the opposite side such apertures are located in those ribs which are skipped on the first mentioned side. This construction tends to avoid the provision of a single continuous longitudinal weakened line.

From the foregoing, the manner in which the device is used will be readily understood. When the device is sold, it may be in the form disclosed in Figure 1, whereby a small amount of the abrasive or steel wool 2 projects below the end of the covering 1. The device may be then held in the hand and used for scouring or polishing purposes until the exposed part of the abrasive 2 is used or become worn down flush with the end of the covering. Thereupon, the end of a fork or other pointed household implement may be inserted in the lowermost opening 8 and a part of the covering torn off on the lowest weakened line or groove 5, so that part of the abrasive will be exposed. This may be continued as long as there is any abrasive material in the holder, it being merely necessary to tear off or remove successive rings on the covering to expose portions of the abrasive material.

It will also be noted that the construction of the cover or casing 1 just mentioned is such that it provides a roughened exterior surface so that it does not become slippery or

difficult to hold in soapy water. As this casing or cover 1 securely grips the abrasive, it does not permit the abrasive to become solidified or compacted and rendered unfit for use 5 nor does it expose to the hands a greater part of the wool than is necessary for actual use.

In the construction disclosed in Figures 3 and 4, the covering disclosed at 9 may be of any suitable material, such as a waterproof 10 fabric, rubber or the like and in this modification of my invention, said covering is of tubular form and consists of a section of material tightly wrapped around the abrasive material 2 and a longitudinally extending 15 edge 10 of the covering is provided with a plurality of spaced inwardly extending slits 11, providing tabs 12 which may be successively grasped to tear off a part of the covering and expose portions of the abrasive 2 as 20 may be required.

In the modification of my invention disclosed in Figure 5, the covering 13 there shown preferably of rubber is provided with a plurality of diagonally extending serrations or threads 14 and this threaded part is provided with punched-out tabs 15 which can be successively grasped so that parts of the covering may be torn or threaded off to expose successive parts of the contained abrasive or wool 2. It will be noted that the threads are "left hand" threads, so that portions of this covering 13 tear off when successive tabs 15 are pulled. It will be seen that the tabs 15 are spaced apart so that there is located intermediate of each pair of tabs, an intervening rib. The casing is thus arranged in order that when each section is torn away, the then remaining lower end of the casing will be in the nature of a continuous rib, preventing inadvertent tearing of the casing while the device is being used for scouring.

In the modification of my invention disclosed in Figure 6, the covering is formed 45 from a single, continuous, spirally wound strip 17, which is provided with transversely-extending weakened lines 18, so that to expose parts of the wool or abrasive, part of the covering 17 is unwound and severed or torn off 50 at any of the weakened lines 18. In this construction, the overlapping parts of the strip 17 may be adhesively joined to maintain the spirally wound covering in position, yet the adhesive is such that it does not possess too 55 great a tenacity to prevent the strip from

being manually unwound and torn away when desired.

From the foregoing, it will be obvious that my device may be embodied in many forms, without departing from the spirit of this invention. Any form of covering used for holding the abrasive should be of sufficient rigidity to hold the abrasive in proper shape and to permit its being in the form of a stick, it will be seen that the unused part of 65 the abrasive is always covered and kept clean and ready for use and that the hands of the user are constantly protected by the covering while the article is being used.

Having described my invention, what I 70 claim is:

1. An article of the class described comprising a holder for a metallic wool abrasive, said holder being composed of a tubular casing provided with spiral exterior ribs, 75 said casing being provided with a plurality of struck out tabs produced by the severance of some of said ribs.

2. An article of the class described comprising a holder for a metallic wool abrasive 80 consisting of a tubular section of exteriorly ribbed rubber, the ribs being severed at spaced points providing pulling tabs for successively tearing away sections of said casing.

3. An article of the class described comprising a substantially cylindrical body of metallic wool abrasive, a container therefor consisting of a ribbed tubular section of resilient impervious material, said container surrounding the body of wool and maintaining it in its substantially cylindrical shape, and weakened at spaced points on the ribs of 85 said container whereby parts of the container may be successively torn away.

4. An article of the class described comprising a holder containing metallic wool abrasive, said holder being composed of a rubber tubular casing adapted to be removed in sections to expose successive portions of 90 its contents.

5. An article of the class described, comprising a tubular casing of flexible water-repellent material containing metallic wool, said casing having a plurality of external ribs, punched-out, tearing tabs provided at 105 spaced intervals in said casing, with one complete rib located between each pair of tabs.

Signed at the city, county and State of New York, this 14th day of January, 1927.

JULES J. BRELL.
